INDICATING, RECORDING, AND/OR CON-
TROLLING APPARATUS

Raymond W. Ross, Philadelphia, Pa., and Sigurd H. Seberhagen, deceased, late of Philadelphia, Pa., by Sophie Seberhagen, executrix, Philadelphia, Pa., assignor to Leeds and Northrup Company, Philadelphia, Pa., a corporation of Pennsylvania

Application April 18, 1936, Serial No. 75,268

45 Claims. (Cl. 234—5.5)

This invention relates to exhibiting instruments and apparatus for indicating, recording, controlling or otherwise measuring the magnitude of any predetermined condition; and more particularly to an apparatus for use in connection with a measuring circuit and including means for intermittently rebalancing the same, of such type, for example, as shown and described in United States Letters Patent No. 1,935,732, granted November 21, 1933, upon the application of L. Y. Squibb.

This application is a continuation-in-part of copending application Serial No. 2,872, filed January 22, 1935, for Indicating, recording and/or controlling apparatus.

While this invention is of general application, it is particularly suitable for application to multiple-record indicating, recording and/or measuring apparatus for use in connection with a measuring circuit and including means for periodically recalibrating the measuring circuit; this invention relates further to the several component operating mechanisms of such an apparatus by means of which the various portions thereof are maintained in synchronism and the phase therebetween accurately adjusted, thus avoiding interference of the separate mechanisms or misleading or irregular records or indications.

More specifically, this invention comprises indicating, recording, controlling and/or measuring apparatus including a primary member movable in response to the magnitude of a condition under measurement, as determined by a measuring circuit; a continuously operated driving element or power mechanism, and a mechanical relay apparatus controlled by the primary movable member and operating periodically to rebalance the measuring circuit, control and operate the indicating and recording unit assembly. The apparatus includes also a recalibrating mechanism operated by the driving element effective periodically to recalibrate the measuring circuit to compensate for variations in any electrical condition of the source of power for the measuring circuit, and means for synchronizing, and accurately controlling the phase relationship between, the mechanical relay apparatus and the recalibrating mechanism.

In case this invention is applied to a printing recorder, as contrasted to a continuous curve drawing recorder, the marker or printing element or assembly is operated by the driving element and is interlocked with the calibrating operating mechanism to prevent operation of the marker during a recalibrating cycle; and there is pro-

vided also means for synchronizing, and accurately determining the phase relation between, the marker operating mechanism and the mechanical relay apparatus. In case this invention is applied to a multiple-record indicating, recording or measuring apparatus; that is, apparatus for measuring a plurality of similar or different conditions at the same or different points or locations, it includes also means rendered inoperative during a recalibrating cycle, for successively advancing the marking element or assembly, preferably in step-by-step motion, and for simultaneously changing the circuit connections of the measuring circuit successively to respond to a plurality of predetermined conditions in a definite sequence, and the apparatus includes also mechanism for synchronizing, and accurately determining the phase relation between, the operating mechanism for advancing the marking element and operating the circuit controller and the mechanical relay apparatus.

This invention comprises also improved and simplified sub-combinations or component mechanisms of a combined indicating, recording and/or measuring apparatus of the type just described by means of which a high degree of accuracy and reliability of operation is attained.

A further feature of this invention comprises an improved recording element assembly particularly suitable for use in the combined apparatus described above, and also an improved universal single or multiple point recorder element assembly, and to new and improved inking devices particularly useful in connection with such recorder element assembly.

The term "measure" is used herein to connote any indication, recording, controlling or other effect which is derived from and constitutes a measure of a given primary condition.

For a better understanding of this invention, together with other and further features thereof, reference is had to the following description taken in connection with the accompanying drawings, and its scope will be pointed out in the appended claims.

In the drawings, Fig. 1 is a view in rear elevation, of a combined indicating-recording apparatus embodying our invention;

Fig. 2 is a front elevation, partly broken away, of the apparatus of Fig. 1;

Fig. 3 is a top plan view of the apparatus of Fig. 1;

Fig. 4 is a cross-sectional view of the recorder element assembly shown in Figs. 1 through 3;

55

Fig. 5 is a cross-sectional detail of a driving connection of the mechanism of Fig. 4;

Fig. 6 is a side elevation of the recorder element assembly of Fig. 4 with a modified inking device;

Fig. 7 is a side elevation of an operating mechanism suitable for actuating the recorder element assembly of Fig. 4;

Fig. 7a is a detail of an operating cam of the mechanism of Fig. 7;

Fig. 8 is a schematic circuit diagram of a measuring circuit and its associated elements with elements corresponding to those shown in the preceding figures identified by like reference characters.

Fig. 9 is a cross-sectional view of the current calibrating operating mechanism along the lines 9—9 of Fig. 3;

Figs. 10 and 11 are, respectively, front and side elevations of a modified form of inking device;

Fig. 12 is an exploded perspective view of selected parts of the mechanism of Figs. 1—9, particularly the calibrating mechanism, the printing mechanism, and associated drive shafts, timing gears and operating cams;

Fig. 12A is a side elevation of one of the discs of Fig. 12 together with a part of its associated follower;

Fig. 13 is a perspective view of a modified form of mechanism suitable for the control of the printing or recording mechanism; and

Fig. 13A is a fragmentary end elevation of Fig. 13.

It is believed a clear understanding of the arrangement and operation of the various parts of the apparatus will be best understood from a complete description of the operation of the apparatus as a whole, and therefore the construction and arrangement of certain of the mechanisms or component parts of the apparatus by themselves will be first described in detail.

Referring now more particularly to Figs. 1, 2, and 3 of the drawings, there is shown one embodiment of this invention comprising indicating, recording and/or controlling apparatus operable in response to changes or variations in magnitude of any desired condition as indicated by a galvanometer G, provided with a pointer or deflecting element 10. The several indicating, recording and/or controlling elements or mechanisms to be described hereinafter may be operated in accordance with deflections of the pointer 10 through any suitable mechanical relay apparatus, although there has been illustrated, by way of example, a particular mechanical relay apparatus, similar to that described and claimed in U. S. Letters Patent No. 1,935,732, granted November 21, 1933, upon the application of L. Y. Squibb.

In brief, the mechanical relay apparatus comprises a pair of clamping members or bars 11 between which the pointer 10 of the galvanometer G normally freely deflects. One of the members 11 is periodically moved toward engagement with each other, and with the pointer 10 by means of linkage elements (not shown) and a cam 12 continuously rotated by a power shaft 13 driven by a motor M through a worm 14' and a worm wheel 14. There are also provided a pair of scissors-like pointer engaging arms or feelers 15 pivoted respectively at 15a on a plate 9 (shown in dotted outline for the sake of clarity) and biased into engagement with each other by a suitable spring 16. The plate 9 is pivoted at its upper end from the frame of the apparatus and

about an axis parallel to the plane of the paper, as viewed in Fig. 1. Secured to the arms 15 are the cam followers 15b, which ride on the cam surfaces 12b of the cam element 12, the arms being thereby separated to disengage the pointer 10 for a predetermined portion of each rotation of the shaft 13.

Also pivoted on the plate 9 at 17a is a clutch arm 17 having a pin 17b adjustably secured in a slot of an upstanding arm 17c. The pin 17b is disposed between the lower portions of the arms or feelers 15 and is adapted to be engaged thereby when the scissors are closed by the biasing spring 16 after release by the cam 12. The outer ends of the clutch arm 17 are provided with clutch surfaces or shoes (not shown) co-operating with a clutch rim 18a of a clutch disc 18. The outer ends of the clutch arm 17 are provided also with cam surfaces or followers 17d disposed in the path of rotation of a pair of cams 19, driven by the shaft 13. The clutch disc 18 is rigidly secured to a shaft 20 (Figs. 2, 3) journaled in the frame of the apparatus.

The manner in which the above described apparatus operates periodically to rotate the shaft 20 through an angle dependent upon and constituting a measure of the deflection of the pointer 10 of the galvanometer G is set forth in detail in the above entitled Squibb patent. In brief, assuming the parts to occupy the positions indicated in Fig. 1, the galvanometer pointer 10 is free to deflect in response to variations in magnitude of the condition to be measured or controlled. At a predetermined point in a cycle of rotation of the shaft 13, as determined by the cam 12, the pointer 10 in its deflected position is clamped between the bars 11. Substantially immediately upon the clamping of the pointer 10 by the bars 11, the cam followers 15b ride off the cam surfaces 12b and release the arms or feelers 15, which move toward engagement with each other under the influence of the biasing spring 16. In case the pointer 10 has previously been deflected in response to a change in magnitude of the condition to be measured, one of the feelers 15 will engage the pointer before the other, which latter then moves beyond its central or neutral position until it deflects the clutch arm 17 an amount corresponding to the deflection of pointer 10. More specifically, the plate 9, prior to release of the feelers, has been moved by the cam 12 about its pivot to disengage the clutch arm 17 from the clutch disc 18 so that the arm 17 is free to move. The lower arm of that one of the feelers 15, which has moved beyond its neutral position as aforesaid, engages the pin 17b secured to the arm 17, and rotates it, about its pivot 17a through an angle proportional to the deflection of the pointer 10; thereafter the cam 12 releases the plate 9 and the arm 17 in its new position is returned into driving engagement with the clutch disc 18a. One of rotating cams 19 then engages its associated cam follower 17d, which has been deflected upwardly into its path of rotation by angular movement of arm 17, and, during continued rotation of the cam, returns the clutch arm 17 to its normal or horizontal position, at the same time driving the clutch disc 18 through an equal angle. The clutch disc 18 is secured to a shaft 20 journaled in the frame of the apparatus, the angular movement of the shaft being utilized to drive the indicating, recording and/or controlling elements of the apparatus. For example, an insulating disc 21, Fig. 2, secured to the shaft 20

may carry a potentiometer 21a cooperating with a stationary adjustable contact 21b, and this 5 slide-wire or potentiometer may preferably be included in a circuit effective to return the galvanometer G to its normal position, as described hereinafter. Also, the shaft 20, Fig. 3, may carry a pulley 22 cooperating with a cord or endless belt 23, Fig. 1, passing over idler pulleys 24 and attached by screw clamps 25b to a carriage 25 carrying the indicating and recording elements.

As shown more clearly in Figs. 4, 6, 7, 12, and 13, the carriage 25 comprises a substantially box-like frame, open at top and bottom, and suitably fabricated from sheet metal. Disposed within the carriage-frame 25 is a driving gear 26 secured on a sleeve 27 journaled in the ends of the frame 25. The respective ends of the sleeve 27 are of reduced diameter and pass respectively through corresponding openings in the ends of the frame 25, Figs. 3, 5, and 12, the shoulders 21s bearing against the inner sides of the ends of the frame to insure lateral movement of the sleeve 27 and carriage as a unit and to permit rotation of gear 26 independently of the carriage 25. A driving connection between the sleeve 27 and shaft 28 is provided by a longitudinal slot or keyway 28a in which is disposed a key interconnecting the shaft and the sleeve 27. As shown more clearly in Fig. 5, a cylindrical key 27a is secured within the sleeve 27 by a set screw 27b, the key 27a sliding with minimum friction in the slot 28a of the shaft 28. Projecting from the carriage 25 are a pair of arms 25a which slidably engage a guide shaft or rod 29 to prevent rotation of the carriage 35 25 about the shaft 28.

A second box-like frame, Fig. 6, having up-standing ears or lugs 30a is pivotally supported from the frame 25 by means of pivot pins 30b passing through apertures of the frame 25 and the up-standing lugs 30a. Journaled between the side bars of the frame 30 and extending at right angles to shaft 28 is a shaft 31 upon which is secured a helical driven gear 33, Fig. 4, meshing with driving gear 26 substantially in a line passing through the axis of the pivots 30b. Also secured to the shaft 31 is a recorder device or printwheel 32 provided with a plurality of printing characters or like marking elements, and an index plate 34. From the front end of the frame 30 or, as viewed in Figs. 4, 5, and 7, at the left end thereof, there extends a U-shaped member, one arm 35 of which constitutes an indicator which cooperates with a stationary scale 36. Depending from the carriage-frame 25 is a V-shaped plate or arm 37 (Figs. 1, 4, 6, and 7) having a pin 38 in its lower extremity disposed to engage peripheral recesses in the index plate 34, as described more fully hereinafter.

A second V-shaped plate or bracket 39 extends 60 upwardly from the forward side bar of the frame 25 and may be integral therewith or, as illustrated in Fig. 4, may be adjustably secured by a screw or nut and bolt 40 passing through a slot in the bar of the frame 25 and a hole in the bracket 39, or vice versa. The bracket 39 preferably extends upwardly at an angle of approximately 45° and journaled therein is a stub shaft 41 upon which is secured a helical gear 42 also meshing with the driving gear 26. A second 65 stub shaft 43 is provided with a threaded extension 43a engaging a threaded recess in the shaft 41 and forms an extension thereof. The shaft 43 is provided with a knurled end 43b to facilitate engagement and disengagement between the 70 shafts 41 and 43.

Mounted on the stub shaft 43 is an inking drum or disc 44 provided with a plurality of peripheral notches or recesses 44a in which are disposed inking pads 44b which may be inked with various distinctive colors. The pads 44b are 75 preferably proportioned to fit closely within the recesses 44a and a retaining disc or plate 45 is secured to the face of the disc 44 by screws 45a additionally to retain the inking pads 44b in the disc 44. The inking drum 44 is loosely journaled on the shaft 43 and, in order to secure proper synchronization between the drum 44 and the printwheel 32, an arm 46 is secured to and projects from the stub shaft 41 and engages in a recess 44c of the drum 44 forming a driving engagement therewith.

In order to tilt or oscillate the frame 30, in which is mounted the printwheel 32, to bring the latter into engagement with the record chart, the frame 30 is provided with an extension or arm 20 30c terminating in a cylindrical guide element 30d disposed in a key or slot 29a in the shaft 29. Movement of the shaft 29 in a clockwise direction (Fig. 4) thereby tilts the frame 30 and the printwheel 32 until the latter engages and registers a distinctive character upon the record chart.

In certain instances, as for example, when the printwheel 32 is provided with a plurality of distinctive record characters, a single color inking pad suffices. In Fig. 6 is shown a modified assembly in which the bracket 39, of Fig. 4, supporting the inking pad drum 44 is replaced by a bracket 47. The bracket 47 terminates in a holder 47a in which is mounted an ink pad 47b registering and cooperating with the several record characters of the printwheel 32. The bracket 47 is secured to the frame 25 by suitable screws or bolts 40 and is preferably interchangeable with the bracket 39, so that either may be replaced by the other simply by releasing the screws or 40 bolts 40.

The printwheel 32 may register its record upon any suitable record chart driven by any well-known mechanism. By way of example only, there is shown (Figs. 1, 2, 3, and 7) a continuous 45 strip chart 50 which, as supplied from a feed roll (not shown), passes over a chart drum or driving roll 51 and thence over a backing plate 52, during which passage the record may be viewed by an observer. By mounting the printwheel 32 with 50 its axis normal to the face of the chart and arranging the characters along a beveled edge thereof the printed record is visible from the front of the instrument as soon as the printwheel is returned to its normal position as shown in 55 Fig. 2 and described with greater particularity hereinafter. Mounted on the main power shaft 13 is a worm 53 (Fig. 7) engaging a worm wheel 54 mounted upon and driving a shaft 55 which, through gearing 56, drives a shaft 57 on which is 60 secured a worm 58 registering with a worm wheel 59 secured to the shaft 60 of the chart drum 51. Consequently the chart 50 is continuously driven at low speed from the power shaft 13.

While the printwheel 32 may be advanced step-by-step by any well-known mechanism to bring in succession its characters into printing positions, it is advantageous to use in accordance with the present invention a mechanism which not only advances the printwheel but also serves 70 periodically to oscillate or tilt the printwheel 32 into momentary engagement or registration with the record chart. To this end there is provided a ratchet mechanism (Fig. 7) which comprises a ratchet wheel 61 secured to the end of the shaft 28, 75

and a double-armed member or bell crank 62 independently movable with respect to but journaled on the shaft 28 and on one arm of which is pivotally mounted a ratchet pawl 63 biased into engagement with the wheel 61 by means of a spring 63a. There is also provided a locking ratchet pawl 64 mounted on a stationary pivot and biased into engagement with the ratchet wheel 61 by a spring 64a, thereby preventing reverse rotation of the ratchet wheel 61. Referring to Fig. 7, the other arm of the bell crank 62 is provided with a slot 62a in which slides a pin 65 adjustably secured in a slot 66a of one arm of a second bell crank 66. The other arm of the bell crank 66 is operated by a mechanism comprising a link 67 and an arm 68 pivoted intermediate its ends on a fixed pivot pin 68a. The link 67 is connected to the end of the arm of the bell crank 66 by a pivot pin 67a, while in its other end is provided a slot 67b in which is adjustably secured a pin 68 journaled in the end of the arm 68. A biasing spring 70 attached to the upper portion of the arm 68 tends to rotate it in a counter-clockwise direction, thus moving the bell crank 62 also in a counter-clockwise direction to advance the ratchet pawl 63 with respect to ratchet wheel 61 so that, upon subsequent return of the operating mechanism to the position shown in Fig. 7, the ratchet wheel 61 will be advanced through a predetermined angle or step. An adjustable stop 71 is provided to limit the throw of the operating arm 68 under the influence of the spring 70.

The operating mechanism above described is normally restrained in a position shown in Fig. 7 by means of a cam follower, shown as a projection or pin 72 (Fig. 12) extending from the lower arm of the member 68 and riding on the face of a cam or disc 73 provided with a single peripheral notch or recess 73a (Figs. 1, 2, and 7a). The disc 73 is driven by a worm wheel 74 engaging the worm 53 driven by the main power shaft 13. Therefore, once each predetermined number of revolutions of the shaft 13, the pin 72 registers with the recess 73a, permitting the arm 68 to move in a counter-clockwise direction under the influence of the spring 70.

It is highly desirable that the print wheel 32 shall be prevented from registering with the record chart during that portion of the cycle in which the clutch arm 17 (Fig. 1) engages the clutch disc 18, since a rotation of the disc 18 might produce a transverse movement of the printwheel carriage during the printing operation and smear or blur the record chart. The timing of the registration of the printwheel 32 with the record chart 51 with respect to the cycle of operation of the mechanical relay apparatus described above is obtained by means of a cam 76 (Fig. 7) mounted on the shaft 13 and provided with a single recess 76a with which cooperates a projection or pin 75 (Fig. 3) adjustably secured in the lower end of the arm 68. It is clear that the cam 73 operates at a speed of a lower order of magnitude than that of the cam 76. Thus, the pin 72 and the disc 73 determine the frequency of registration of the printwheel 32 with the record chart 51, as determined by the gear ratio between the worm 53 and worm wheel 74, while the pin 75 and the cam 76 accurately time or phase the registration of the print wheel with respect to the angular position of shaft 13 and its cam 12, or with respect to a desired portion of the cycle of operation of the mechanical relay apparatus. Both the disc 73 and the cam 76 are

adjustable with respect to their respective shafts 14a and 13, to insure proper phasing with respect to the mechanical relay.

It is often desirable automatically to switch the circuit of the galvanometer G between several measuring circuits simultaneously with the successive step-by-step movement of the printwheel 32 and the inking drum 44. To this end, the shaft 28 which imparts the step-by-step movement to the printwheel 32 and the inking drum 44 carries a gear 77 which, through an intermediate idling gear 78, drives a gear 79 attached to a shaft 80. Upon the shaft 80 (Fig. 1) is mounted a bevel gear 81 cooperating with a second bevel gear 82 secured on the shaft 83, on the lower end of which is attached a rotatable brush member 84. The member 84 cooperates with the stationary member 85 carrying a plurality of segmental annular contact members 85a. The selector switch comprising members 84 and 85 is preferably enclosed within a casing 87 which may contain oil or other suitable lubricating medium.

The operation of the above described automatic multiple-record indicating and recording apparatus will be understood more clearly by now referring to Fig. 8 in which is shown a schematic diagram of a system, including certain of the several elements thus far described, for successively measuring the magnitudes of a plurality of conditions at the same or different locations, for example, the temperatures at a plurality of points or locations; in one specific example which has operated satisfactorily, 16 points. Thus, by multiple-point recording and/or indicating means, reference is made to provisions for utilizing the same instrumentality for successively measuring and/or recording conditions as measured at a plurality of points by condition-responsive means individual to each point or location. In Fig. 8 it is seen that the measuring circuit includes a potentiometer comprising a slide-wire or adjustable resistance 21a having an adjustable contact 21b connected in series with fixed resistors 87a and 88 and energized from a source 89 of current, such as a battery 89, through a calibrating resistance 90 provided with an adjustable contact 90a. The galvanometer G is connected in circuit successively with one of several thermocouples 92 or other primary condition-responsive elements through a two-position switch 91, when in its left-hand position, as seen in Fig. 8, and in series with that portion of the potentiometer 87a-21a-88 comprising the resistance 87a and the left-hand portion of the slidewire 21a.

It is now believed that a comprehensive understanding of the invention, including the construction, arrangement and operation of the apparatus, will be facilitated by a description of the operation of the organization as a whole. To this end it will be assumed that the movable element of the selector switch has just been moved to the position shown in Fig. 8 of the drawings, in which it completes the circuit through one of the several thermocouples 92. If the temperature as measured by the particular thermocouple 92 is different from that indicated by the preceding thermocouple and with which the setting of the adjustable contact 21b of the slidewire 21a corresponds, an unbalance voltage will appear in the circuit of the galvanometer G which will deflect its pointer 10. When the pointer 10 is thus deflected, a motion will be imparted to the shaft 20, Figs. 2 and 3, carrying the slidewire 21a which, within predetermined limits, is representative of,

and a measure of, the deflection of the pointer 10, as described above. The connections of the galvanometer G and the sense of operation of mechanical relay apparatus are such that the slide-wire 21a will be moved in a sense which will tend to rebalance the measuring circuit of Fig. 8.

In case the initial movement of slide-wire 21a is insufficient or over-sufficient to rebalance the measuring network, the mechanical relay apparatus repeats its cycle of operation again to adjust the potentiometer slide-wire 21a to rebalance the measuring circuit. The relay apparatus, before printing, may operate for a predetermined number of revolutions of the shaft 13, such as 24, which is sufficient to insure a complete balancing of the measuring circuit of Fig. 8 even under extreme changes in electromotive force between successive thermocouples occasioned by widely varying temperatures at the different measuring points.

Simultaneously with movement of the slide-wire 21a the carriage 25 and associated elements are, by the driving pulley 22 and the endless belt 23, moved across the chart 51. The position of the indicator 35 with reference to the scale 36 (Fig. 2) is a measure of the magnitude of the condition under measurement. As soon as the potentiometer circuit is rebalanced a direct reading may be taken which will correspond with great precision to the magnitude of the condition under measurement.

After a predetermined number of cycles of operation of the mechanical relay apparatus, corresponding to the number of rotations of shaft 13 as determined by the ratio of the worm 53 and the worm wheel 74 (Figs. 2, 7, and 12) have been completed, the disc 73 will occupy a position such that the pin 72 projecting from the lower end of the arm 68 engages with the peripheral notch 40 or recess 73a of the disc preparatory to the printing or recording operation.

Just prior to registration of recess 73a and pin 72, an effective inking of the uppermost marking element of the printing wheel 32 is accomplished by means of a raised or punched out portion 73b (Figs. 7a and 12A) corresponding with the leading end of the notch or recess 73a of the disc 73. Thus as the raised portion 73b is moved into engagement with the pin 72, a slight clockwise movement is imparted to the arm 68 which movement is transmitted through link 67, bell crank 66, shaft 29 and extension 30c to rotate the uppermost character of print wheel 32 into firm engagement with the corresponding one of the inking pads 44b carried by the disc 44. A slight additional movement of the disc 73 releases arm 68 which then moves through a small angle in a counterclockwise direction to its original position. By this means an effective inking of the several marking elements of the disc or print wheel 32 is accomplished, at the same time avoiding the continuous pressure between the print wheel 32 and the disc 44 which would result in increased friction or possible binding of the elements of the recorder assembly.

As stated above, for the printing operation the release of the operating arm 68 is accurately timed, with reference to the operating cycle of the relay mechanism, by the cam 76 and the auxiliary pin 75. Thus, immediately after the cam 72 disengages the clutch arm 17 from the disc 18 the cam 76 is arranged to move its recess 76a into registration with the pin 75 carried by the arm 68. This arm is thereby released for movement in a counter-clockwise direction under

the influence of the operating spring 10. As the arm 68 moves, the pins or followers 72 and 75 respectively enter recesses 73a and 76a and the bell crank 66, now rotated by operating arm 68 and link 67 in a clockwise direction, drives, in a clockwise direction, the shaft 28 which in turn moves the print wheel supporting frame 30 pivoted at 30b through a corresponding angle in a counter-clockwise direction, the movement being sufficient to insure registration of the print wheel 32 with the record chart 51. The duration of the time the print wheel 32 is in engagement with the chart 51 is determined by the size or extent of the recess 76a of the cam 76. Since the chart is continuously driven from the main shaft 13 the recess 76a has a configuration such that the print wheel 32 moves rapidly into and out of engagement with the chart thereby to prevent blurring or smearing and to insure a single imprint of the record mark or indicia by the print wheel 32 upon the record chart.

It may here be observed that the axis of the print wheel 32 is normal to the plane of the face of the chart 51 (Fig. 2) and that during the printing operation the print wheel or disc 32 registers with the chart forwardly and substantially below the top of the chart drum. In consequence, as soon as the print wheel 32 is returned to its normal position and out of engagement with the chart 51, the record left thereon is immediately and readily visible from the front of the apparatus, as shown in Fig. 2.

Simultaneously with the printing operation, the bell crank 62 is by clockwise movement of bell crank 66 rotated in a counter-clockwise direction, the ratchet or pawl 63 merely sliding over one tooth of the ratchet wheel 61, which is locked against rotation in this direction by the locking ratchet pawl 64. However, as the arm 68 is returned to the position shown in Fig. 7 by the cam 76 operating on the pin 75, the shaft 29 is again rotated to the position shown in Fig. 7, returning the print wheel 32 to its normal position. During this return motion, the bell crank 62 is rotated in a clockwise direction and drives the shaft 28 through a similar angle by means of the ratchet pawl 63. This rotation of the shaft 28 is adjusted by means of the adjustable pins 65 and 69 to correspond exactly to the angle between adjacent record characters or marking elements on the periphery of the print wheel 32. The shaft 28 through the helical gears 26, 33 and 42 drives the print wheel 32 and the inking drum 44 through corresponding angles, so that the print wheel 32 is in position to register the condition at a succeeding location or point under measurement in response to a change in circuit connections as is presently to be described.

As mentioned above, the spiral gear 33 meshes with spiral gear 26 on the pivotal axis through screws 30b. This is done in order to prevent rotation of the print wheel upon its movement into engagement with the chart.

In order substantially to eliminate errors in the registration of the print wheel 32 on the record chart 51, due to any lost motion in the driving mechanism between the shaft 13 and the print wheel 32, an index plate 34 is carried by the same shaft as the print wheel 32 and is rigidly secured thereto. This index plate 34, upon depression of the print wheel 32 as described above, engages a projecting pin 38 on the depending stirrup or bracket 31 secured to the frame 25 of the indicating and recording element assembly, and guides the print wheel during printing.

The peripheral notches or indentations of the index plate 34 are in exact angular alignment with the record characters or printing elements of the print wheel 32 so that the angular position of the print wheel 32 is accurately determined for each printing registration, thereby insuring that each character is moved flat against the chart 51. A further important function is to prevent rotation of the print wheel 32 and to prevent lateral displacement of the record which might otherwise result. In this manner, all records are accurate to within one-quarter of a percent and no inaccuracies are introduced by lateral displacement of the printed record.

15 In brief then, the galvanometer G is automatically and successively connected in circuit with the several thermocouples 92 and, after each such connection, the measuring circuit of Fig. 8 is automatically rebalanced by the above described 20 mechanical relay apparatus until the deflection of the galvanometer is reduced to zero. After a number of cycles of operation of the mechanical relay apparatus sufficient to insure the rebalancing of the measuring circuit, the recording mechanism, which has been moved to a new position with respect to the chart, is automatically operated to register an indication on the record chart of the magnitude of the condition existing at the particular point under measurement and the indicator 35 indicates this value on the cooperating scale 36. Thereafter, the galvanometer is successively connected in circuit with the other thermocouples and the above described cycle of operation is repeated. For each point, the indicator 35 and recorder element assembly is moved transversely of the scale 36 (Figs. 2, 3, 4, 6, and 7) and the record chart 50, so that the indicator 35 will indicate on the scale 36 the magnitude of the condition existing at the point of the measurement; this magnitude may be registered on the record chart graduated as the scale 36 by means of the impression left by print wheel 32. At the same time a numeral 32a on the front face of the print wheel 32, appearing through the opening in the mask 32b, indicates the number of the control point at which the measurement is being taken. Preferably a corresponding numeral is printed on the chart by the print wheel 32.

50 It will be noted also that the connection of the galvanometer successively into the several thermocouple circuits is automatically synchronized with the step-by-step movement of the print wheel 32 and the inking drum 44 through the gearing 77—78—79—81—82, described above.

55 It is well understood that the voltage of a battery, such, for example, as that utilized to energize the potentiometer measuring circuit of Fig. 8, varies appreciably with time, and that the accuracy of measurement, as determined by the above described apparatus, depends upon the constancy of current to the slidewire 21a; that is, the constancy of the terminal voltage of the battery 89. In order to compensate for variations in voltage of such a battery, it is desirable periodically to recalibrate or restandardize the measuring circuit by substituting therein a standard electrical unit, preferably an auxiliary standard cell or source developing a constant or 70 standard electromotive force. For example, referring to Fig. 8, if the switch 91 be operated to its right-hand position, the galvanometer G will be connected directly across the potentiometer circuit in series with a standard cell S supplying such an electromotive force. Under normal con-

ditions, the voltage of the standard cell S just balances that across the potentiometer comprising the resistances 87a and 88 and the slidewire 21a. If, however, the voltage of the battery 89 has changed, the measuring circuit will no longer be balanced. It may be restored to balance by varying any desired electrical condition or constant of the measuring circuit, for example, by adjusting the contact 90a of the calibrating resistance 90.

10 It is desirable to effect this restandardization or recalibration automatically and periodically, for example, every half or three-quarters of an hour, corresponding to a predetermined higher number of revolutions of shaft 13. To this end, 15 there is provided an arm 93 (Figs. 1-3 and 12) pivotally supported at 93a, and periodically released to operate, through the auxiliary pivoted arm 94 and projection 94a, the switch 91 above described in connection with Fig. 8. Thus, depression or clockwise rotation of the projection or element 94a, Figs. 1 and 12, corresponds to a movement of the switch 91 of Fig. 8 to its right-hand position.

20 The time between successive operations of the 25 arm 93 and of the switch 91 is determined by means of an adjustable rotating cam or disc 95, having a single peripheral notch or recess 95a, driven from the shaft 13 through an intermediate double-worm gear reduction drive. The gear 30 ratio, provided by the aforesaid drive and comprising worm 96 secured to shaft 13, and driving worm wheel 97 on shaft 97b which in turn drives through its associated worm 98a and worm wheel 98 the disc 95, is very high, for example, of the 35 order of 1200 to 1; that is, for twelve hundred revolutions of the shaft 13 the disc 95 completes one revolution. During that revolution the peripheral notch 95a is moved into registration with the projection or cam follower 93b of the arm 93 40 which is biased for clockwise rotation, as by a spring 93c.

45 Immediate movement of the arm 93, however, is prevented until the recess 101a of an adjustable cam 101 is moved into registration with an 50 adjustable cam follower or pin 102, Figs. 9 and 12, carried by the arm 93. The delayed movement of arm 93 is for the purpose of preventing operation of the switch 91 until the galvanometer needle or pointer 10 is clamped between the bars 55 11, Fig. 1. To this end, the angular position of the cam 101 is predetermined with respect to the shaft 13 and its cam 12, so that after registration of notch 95a with projection 93b, registration of recess 101a with pin 102 occurs substantially concurrently with, or immediately after, the clamping of pointer 10. This phasing or timing is readily accomplished by proper angular adjustment of the shaft 97b and the cam 101 provided for by a split collar 97a, Fig. 3, of worm wheel 97. In consequence, violent swinging or deflection of the galvanometer pointer 10 incident to the opening and closing of switch 91 is prevented. Thus the cam 95 and projection 93b determine the frequency of recalibration as 60 determined by the gear ratio of the double-worm drive, while the cam 101, operating at a substantially higher speed than cam 95, and the projection 102 accurately phase or time the operation of the switch 91 with the aforesaid desired portion of the cycle of operation of the mechanical relay mechanism.

65 Assuming now that the galvanometer needle 10 is clamped into a fixed position by the bars 11 and that disc 95 and cam 101 occupy positions for 70 75

recalibration, the arm 93, under the influence of the relatively strong spring 93c, rotates about its pivot 93a in a clockwise direction, rotating with it the arm 94 whose projection 94a operates the switch 91 to establish the recalibration circuit-connections. The aforesaid clockwise rotation of arm 94 increases the tension in a return spring 94b connected to that arm and to a fixed support as well as the tension in a spring 99b which interconnects one end of an arm 99 and a depending projection 94d of the arm 94. Obviously, the main operating spring 93c is powerful enough to overcome the opposition offered by springs 94b and 99b to movement of arm 93.

The biasing force developed by the spring 99b however tends to rotate the arm 99, pivoted for independent movement on the shaft 97b, in a clockwise direction thereby to move a clutch disc 100 pivotally supported at 100a on the lower end 20 of the arm 99 into driving engagement with the rim or flange 22a of the pulley 22. Supported on the friction disc 100 is the calibrating resistance 90 shown in Figs. 2 and 12 in the form of a slidewire and automatically adjustable to compensate for deviation from a predetermined value of the voltage of the battery or source of supply 89.

Since, as described above, the switch 91 is operated at the time the pointer 10 is clamped, it is undesirable to operate the friction disc 100 into driving engagement with the pulley 22 until later in the cycle of operation of the mechanical relay; that is, until after the feelers 15, Fig. 1, have set the clutch arm 17 to correspond with the galvanometer deflection and the cams 19 have thereafter returned the clutch arm 17 to its horizontal or neutral position. Therefore, immediately prior to operation of the switch 91 by arms 93 and 94, a cam 103, adjustably carried on, and driven by the shaft 97b in predetermined phase relation with respect to shaft 13 and its cam 12, and retarded in phase with respect to cam 101, moves its pointed projection 103a against one end of an arm 104 pivoted intermediate its ends on the frame at 104a. The opposite end of the arm 104 cooperates with the arm 99 to prevent movement thereof, by means of a slot 104b engaging a pin 99e projecting from the rear of the arm 99 as viewed in Fig. 2 but shown on the front 50 of the arm for convenience in Fig. 12. The pointed projection 103a is by shaft 97b moved clear of the lever 104 immediately after the return of the clutch bar 17 to its horizontal position. The spring 99b is then effective to rotate 55 the arm 99 until the aforesaid driving connection between clutch disc 100 and pulley 22 is effected.

The calibrating mechanism is now in readiness for recalibration of the measuring system, as the potentiometer circuit of Fig. 8. Since the recalibration of the potentiometer circuit occurs at predetermined time intervals, as determined by the aforesaid double-worm gear drive, and independently of the position of the selector switch 85 or of the printing and/or recording mechanism, successive calibrations may take place with the selector switch in different positions.

Therefore, suitable mechanism is provided to prevent operation of the selector switch 84-85 and the printing and/or recording mechanism 70 during the operations constituting the recalibrating cycle. In one form of our invention, this mechanism comprises a disc 107 adjustably supported on a worm wheel 105 by means of screws 107b driven by a worm 106 secured to the shaft 74a, a projection 107a on the disc 107 cooperat-

ing, when in given angular position, with a projecting arm or stop element 68b to prevent counter-clockwise rotation of the operating arm 68. The phase or angular relationship between the projection 107a of the disc 107 and the notch 95a of the disc 95, taken in conjunction with their respective gear ratios from the main shaft 13, is predetermined so that the projection 107a is always moved below or in the path of stop element 68b after notch 95a registers with projection 93b and before the cam 16 and disc 73 occupy positions for printing and/or recording operations. Therefore, even though the arm 68 is, by disc 73 and cam 16, freed for actuation of the switch 84-85 and the printing and/or recording mechanism, such operation cannot occur until the projection 107a moves out of engagement with stop element 68b at which time recalibration has been completed.

Continuing with the operation of the recalibrating mechanism, shortly after the clamping of the pointer 10 and the deflection of the clutch bar 17, the feelers 15 by cam 12 are spread and one of the clamping bars 11 operated to release the pointer for deflection. The galvanometer 20 pointer then deflects in accordance with any unbalance which may exist due to change in the voltage of battery 89. During the time the needle or pointer 10 is moving to its new position, the clutch arm 17 is returned to its neutral or horizontal position and the aforesaid driving connection completed between the rim 22a secured to pulley 22 and the friction disc 100. Thereafter the needle is clamped by bars 11 in its new position, the feelers again move the clutch arm to an 30 angular position corresponding to the degree of deflection of the galvanometer pointer from its neutral position. The restoring cams 19, after arm 17 again engages the clutch disc 18, return arm 17 to its horizontal position. In this case the 35 corresponding angular movement of arm 17 and clutch disc 18 is by shaft 20 and rim 22a transmitted to the friction disc 100 which moves the slidewire 90 to a new position. The direction of movement of the slidewire is, as referred to the 40 circuit of Fig. 8, in the direction to correct for the extent of deviation in the voltage of battery 45 89 from its predetermined value.

The foregoing cycle of operations is repeated several times, eight cycles being safely sufficient, 50 to insure that the slidewire 90 is moved accurately and with great precision to a position where the potentiometer voltages as derived from the battery 89 and the standard cell S are in exact balance. The number of cycles of operation, 55 preferably about eight, is determined by the shape and extent of the recess 101a and its speed as compared to that of the shaft 13. Thus after the shaft 13 has completed eight revolutions, corresponding to the aforesaid eight cycles of operation, the cam 101 occupies a position to initiate counter-clockwise rotation of arm 93. Additional rotation of the cam 101 raises the pin or projection 102 from recess 101a thereby returning the arm 93, against the bias of the 60 main spring 93c, to its original position. The arm 94, under influence of the spring 94b, moves with or follows after the arm 93 to release the switch 91 which is automatically returned to the position shown in Fig. 8, as by resilient members upon 65 which the switch contacts are mounted. In addition to predetermining the number of cycles for recalibrating the circuit, the trailing operating surface of the cam 101 is phased or angularly disposed with respect to shaft 13 and cam 12 so that 70 75

the return of the potentiometer system to one of elements 92 occurs during that portion of the mechanical relay cycle when the galvanometer pointer is clamped in a fixed position.

5 The driving connection between the recalibrating slidewire 90 and the rim 22a is broken by reason of the engagement of arm 94 with the adjustable set screw 99d carried by arm 99. Thus as arms 94 and 99 are rotated in a counter-clockwise direction by the spring 94b, the friction disc 100 and slidewire 90 are returned to their original positions, Figs. 2 and 12.

10 The three-part calibrating mechanism comprising arms 93, 94, and 99 together with their associated biasing springs and pivotal mountings is particularly well adapted for the purposes and functions described above.

15 As explained above, the voltage of the battery 89, with use and over a period of time, gradually decreases in value so that the slidewire 90 during a relatively long period, which may be of the order of six months, will be substantially entirely excluded from the potentiometer circuit. To show the position of the slidewire and generally to indicate the condition of the battery, an index 99f may project from a portion of the frame, or as illustrated, Fig. 2, from the arm or lever 99 and may cooperate with graduations or an arrow 100b marked on the disc 100. In any event, when the arrow and index are substantially in alignment, all of the slidewire 90 has been excluded from the circuit indicating that no further correction for decreased voltage may be accomplished by the slidewire 90. For continued accuracy a new or re-charged battery must then be included in the circuit, or the supply voltage as applied to the measuring circuit otherwise increased.

20 Continuing with the operation of the apparatus, the projection 107a of disc 107 frees the arm 68 after the galvanometer is again connected in circuit with one of the condition responsive elements 92 and before the cam or disc 73 and cam 76 again occupy positions for the printing and/or recording operations. In addition to being phased with respect to disc 95 and cam 101, the projection 107a, by reason of its angular position and the gear ratio between worm 106 and worm wheel 105, is moved out of registration with stop element 68b after the recess 73a of disc 73 moves beyond projection 72. In this manner the first printing and/or recording operation subsequent to recalibration occurs after substantially the full number of cycles of operation of the mechanical relay, thereby insuring the rebalance of the circuit before printing; that is, recalibration requires eight cycles of operation; twenty-four cycles are provided between each printing operation. Thus after recalibration the mechanical relay apparatus operates at least sixteen times to insure accurate indication of the magnitude of the condition under measurement. It may here be observed that unbalance of the circuit (Fig. 8) during recalibration is independent of the position of slidewire 21a. Consequently the carriage 25 and frame 30 are moved but a slight amount during recalibration. Moreover, since the switch 84-85 is retained in fixed position during recalibration, the galvanometer is reconnected in circuit with the particular one of elements 92 with which it was connected just prior to initiation of the recalibrating cycle.

25 If the foregoing provisions were not made, a printing operation might occur during calibration; in that event the resulting record on the

chart 51 would be confusing and of little value. Moreover, there would be lost a record of the condition indicated by one of the elements 92.

30 In accordance with the present invention, however, the operation of the printing and/or recording mechanism is interrupted until after completion of the calibrating cycle and until after the mechanical relay mechanism has again rebalanced the circuit and moved the carriage 25 and print wheel 32 to a position with respect to 10 the chart which is an accurate indication of the magnitude of the condition under measurement.

35 In one embodiment of the invention recalibration was provided for each 1200 revolutions of shaft 13, or after each forty-ninth printing operation. Thus with the sixteen control elements 92, it will be seen that each successive recalibration cycle takes place with the selector switch 84-85 one position beyond its preceding position, or angularly displaced from the position corresponding to the preceding recalibrating cycle. In this manner maximum average accuracy for all points may be attained, particularly for a case where there is a measurable drift in voltage of the supply between successive recalibrating 25 cycles.

40 Now that the principles of the present invention are understood, it will be apparent the recalibrating mechanism is applicable to Wheatstone bridge circuits, in which case the slidewire 90 may be included in the ratio arms of the bridge while a standard resistance or impedance device is by switch 91 substituted for one of the elements 92.

45 From the above, it is seen that there is provided a full automatic indicating, recording and/or controlling apparatus which successively indicates, records, and/or controls in accordance with, the conditions measured at a plurality of points, and which automatically recalibrates or restandardizes the measuring circuit, at the same time avoiding any interference between the operations of the several component mechanisms.

50 In Figs. 10 and 11 is shown a modified and simplified form of inking device which, in certain instances, may be used in place of the device 44 of Fig. 4. This device comprises essentially a pair of spiders 110 which may be integral with, or firmly secured to, a central hub adapted for mounting on the shaft 43, as in the case of the inking device 44. The several arms 110a of the spiders 110 are provided with radial slots 110b. The spiders 110 may conveniently be formed of sheet metal so that the slotted arms 110a have a substantial resilience. Near the outer end of each of the radial slots 110b is formed a notch or recess adapted to receive and resiliently retain an arbor 111a of an inking pad 111 which may be of any suitable shape. The arbors 111a and the notches in the slots 110b may be of any suitable shape. In case round inking pads are employed so that their angular relation is unimportant, the arbors 111a may be round, while the shape of the notches is unimportant. However, in case square inking pads are employed, as shown, the arbors 111a are preferably non-circular and of a configuration complementary to the notches in the slots 110b; for example, as shown, the arbors 111a may be square, fitting into V-shaped notches in the slots 110b. The inking pads 111 may be closely fitted upon the arbors 111a or may be retained in position solely by the arms 110a of the spiders 110 which firmly grip the arbors 111a. The inking 75

device of Figs. 10 and 11 may be used directly in place of inking devices similar to 44 in the re-order element assembly of Fig. 4.

In Fig. 13 there is shown a modified form of ratchet mechanism which may replace the cam 18, disc 18, disc 181 and their associated driving gears. This ratchet mechanism comprises a U-shaped frame 115 loosely journaled on the shaft 80. A link 116 pivotally connected to one frame-arm 115a at 117 oscillates the frame 115 under the control of a crank formed by disc 118 secured to shaft 13 and supporting from its face a pin 119 pivotally engaging the opposite end of the link 116. In order to phase or time the operation of the print wheel 32 (not shown in this figure) a ratchet wheel 120 is secured upon a sleeve 121, loosely journaled on shaft 80. A cooperating pawl 122, journaled on a rod or shaft 122a secured between opposite arms of frame 115, is biased into engagement with the ratchet wheel 120 by leaf spring 123 and serves to rotate the ratchet wheel a predetermined amount every time the shaft 13 or pin 119 completes a revolution. By predetermining the position of a cam 123 carried by the sleeve 121, it will be apparent that for a given number of revolutions of the shaft 13 the cam 123 will be rotated through 360°. Thus this cam is phased, and the ratchet mechanism adjusted, so that just prior to completion 30 of the cycle of operations of the mechanical relay for a given control point, a projection 123a of the cam 123 is moved against a lateral projection 125a of a crank arm 125 pivoted from the frame at 126, and thereby rotates the crank arm 125 in a clockwise direction as viewed in Fig. 13, against the bias of a spring 127, and a second spring 128, connected to the frame and to a pin 129 eccentrically mounted on a disc 130 which itself is secured to an operating shaft 131. The outer or free end of the crank arm 125, being beneath the pin 129, is effective to rotate the shaft 131 in a counter-clockwise direction. Rigidly secured to shaft 131, as by pins 132, is a rod 133 engaged by projections 134 of a frame 135, in which is journaled the print wheel 32 (not shown in Fig. 13). Accordingly, the counter-clockwise rotation of shaft 131 rotates the frame 135 in a clockwise direction about pivots 30b to move the print wheel firmly into engagement 50 with the inking disc 44.

As the pawl 122 rotates the ratchet gear 120 and cam 123 an additional distance, a recess 123b is moved into registration with the lateral projection 125a. This recess may be next to the projection 123a or separated therefrom a slight amount so that as the projection 123a is moved beyond the projection 125a the springs 127 and 128 are effective to return the respective crank arms 125 and 131, 133 to their original positions, 60 the print wheel at the same time being moved out of engagement with the inking disc 44. In any event, as soon as the recess 123b registers with the extension 125a, the springs 127 and 128 are effective to rotate respectively the crank arm 125 in a counter-clockwise direction, and the disc 130 and shaft 131 in a clockwise direction. In this case the direction and resulting extent of movement of the frame 135 is sufficient to permit the print wheel to move in a counter-clockwise direction and into engagement with the chart to register thereon one of the characters of the print wheel.

As most clearly shown in Fig. 13A, the printing operation occurs when the frame 115 has 70 been moved substantially to its limit of clockwise

rotation, or after the outer end of frame-arm 115b is below the projection 125a. Accordingly, as the crank arm 125 rotates counter-clockwise, the projection 125a moves over the upper cam surface 115c of frame-arm 115b. Further rotation of the drive shaft 13, now rotates the frame 115 in a counter-clockwise direction, the cam surface 115c then acting on the projection 125a to return the crank arm 125, shaft 131, and the print wheel to their original positions against the bias of the springs 127 and 128. Just prior to the last-mentioned return movement of cam 123, a second cam 136 carried by sleeve 121 occupies a position such that its recess 136a registers with one pawl 137a of a double-pawl member 137 journaled on rod 122a and biased for clockwise rotation by springs 138. The other pawl 137b of member 137 normally retained in a lifted, ineffective position, upon registration of recess or notch 136a and end 137a, moves downwardly into engagement with one tooth of a ratchet wheel 139 secured to the shaft 80. In consequence, the shaft 80 is rotated, as the print wheel is returned to its original position, an amount sufficient to move the selector switch 25 84-85 for connection of a different one of the elements 92 in the potentiometer circuit. The ratchet wheels, and crank 118, 119 are phased with respect to shaft 13 so that the switch movement is completed while the galvanometer pointer 30 is clamped in a fixed position.

The recalibration cycles are timed and controlled by the disc 85 and cam 101 in the manner described above. However, as soon as the arm 93 is moved downwardly by the spring 93c, a cam 140 journaled on shaft 80 is rotated in a counter-clockwise direction by a crank journaled in the frame F, one end of which is by link 141 pivotally secured to arm 93 while its opposite end is by link 142 pivotally secured to the cam 140. By 40 the aforesaid rotation a lower end 140a of the cam is moved toward or against the projection 125a to prevent movement thereof even though the cam 123 moves to the printing position, i. e., a position with the notch 123b in registration 45 with projection 125a. At the same time the upper end 140b of the cam is moved toward or against a pin 143 carried by at least the pawl 137b to prevent movement thereof upon registration of pawl 137a with notch or recess 136a. In this 50 manner the operating means for the selector switch 84-85 and the printing and/or recording mechanism is rendered ineffective during calibration. The timing and phasing in other respects may be and preferably is identical with 55 the modification of our invention previously described.

While there has been described what at present is considered the preferred embodiments of the invention, it will be obvious to those skilled 60 in the art that various changes and modifications may be made without departing from the invention, and therefore the appended claims cover all such changes and modifications as fall within the spirit and scope of the invention. 65

What is claimed is:

1. In a self-balancing measuring system including a measuring circuit, a driven member including a circuit adjusting element, a mechanical relay for driving said adjusting element by a 70 plurality of decreasing steps to a circuit rebalancing position and including a control element periodically released for deflection in accordance with the sense and extent of unbalance of said circuit, relay driving means including a 75

driving shaft, means operable by said shaft to release said control element and effect a step-by-step movement of said driven member corresponding to the sense and extent of deflection of said control member, the combination of transfer means periodically operable after completion of a predetermined low number of revolutions of said shaft for subjecting said circuit in predetermined sequence to a plurality of conditions, an interlock operable after a predetermined higher number of revolutions for retaining said transfer means in a fixed position irrespective of the completion of said lower number of revolutions, calibrating means, and means operable during only a fraction of said lower number of revolutions for including said calibrating means in said circuit and for effecting under control of said relay recalibrating adjustment of said circuit, said last-named means thereafter excluding said calibrating means from said circuit whereby said relay during the remaining fraction of said lower number of revolutions rebalances said circuit prior to operation of said transfer means.

2. In a self-balancing measuring system including a measuring circuit, a driven member including a circuit adjusting element, a mechanical relay for driving said adjusting element by a plurality of decreasing steps to a circuit rebalancing position and including a control element periodically freed for deflection in accordance with the sense and extent of unbalance of said circuit, relay driving means including a driving shaft, means operable in response to each revolution of said shaft to free said control element and effect a step-by-step movement of said driven member corresponding to the sense and extent of deflection of said control element, the combination of transfer means periodically operable from one to another of a plurality of positions after completion of a predetermined low number of revolutions of said shaft for subjecting said circuit in predetermined sequence to each of a plurality of conditions, calibrating means for said circuit, means operable in timed relation with said transfer means for periodically rendering said calibrating means effective so that each successive operation of said calibrating means occurs for a different position of said transfer means, and means for preventing operation of said transfer means during operation of said calibrating means.

3. In a self-balancing measuring system including a measuring circuit, a source of supply therefor, a primary member movable from a neutral position in accordance with variations in magnitude of a condition under measurement as determined by said measuring circuit, a secondary movable member, means operable by said secondary member to rebalance said circuit, operating means for said secondary member controlled by said primary movable member for periodically actuating said rebalancing means to rebalance said measuring circuit, mechanism for periodically recalibrating said measuring circuit comprising means for adjusting an electrical condition thereof, a standard electrical unit, circuit controlling means for connecting said standard unit in said measuring circuit in opposition to said source of supply, the combination of a continuously rotating cam provided with a peripheral recess, a cam follower normally bearing upon the face of said cam and biased into said recess, means responsive to the entry of said follower into said recess for actuating said cir-

cuit controlling means and for effecting an interconnection between said secondary movable member and said adjusting means, and an auxiliary cam for disengaging said follower from said recess.

4. In a self-balancing measuring system including a measuring circuit, a source of supply therefor, a primary member movable from a neutral position in accordance with variations in magnitude of a condition under measurement as determined by said measuring circuit, a secondary movable member, means operable by said secondary member to rebalance said circuit, operating means controlled by said primary movable member for periodically moving said secondary member to effect said rebalance of said measuring circuit, mechanism for periodically recalibrating said measuring circuit comprising means for adjusting an electrical condition thereof, a standard electrical unit, circuit controlling means for connecting said standard unit in said measuring circuit, the combination of a continuously rotating cam provided with a peripheral recess, a cam follower normally bearing upon the face of said cam and biased into said recess, means responsive to the entry of said follower into said recess for actuating said circuit controlling means and for effecting an interconnection between said secondary movable member and said adjusting means, and additional means operating at a higher speed, and of a different order of magnitude than said cam, for accurately and additionally controlling entry of said follower into said recess.

5. In a self-balancing measuring system including a measuring circuit, a source of supply therefor, a galvanometer connected to measure the unbalance of said circuit, a driven shaft, mechanical relay apparatus, including a continuously rotating driving shaft, for periodically adjusting said driven shaft under control of said galvanometer, and means operated by said driven shaft to rebalance said measuring circuit, mechanism for periodically recalibrating said measuring circuit comprising means for adjusting an electrical condition thereof, a standard electrical unit, circuit controlling means for connecting said standard unit in said measuring circuit, the combination of a rotatable cam, a double-worm gear reduction for driving said cam from said driving shaft, a cam follower, means responsive to movement of said follower relative to said cam to actuate said circuit controlling means and to effect an interconnection between said driven shaft and said adjusting means, a second cam driven by the first worm wheel of said gear reduction, and a follower for said second cam acting conjointly with said first follower accurately to phase the operation of said actuating means with respect to the cycle of operation of said mechanical relay apparatus.

6. In a self-balancing measuring system including a measuring circuit, a source of supply therefor, a primary member movable from a neutral position in accordance with variations in magnitude of a condition under measurement as determined by said measuring circuit, a secondary movable member, means operable by said secondary member for rebalancing said measuring circuit, operating means controlled by said primary movable member for periodically actuating said rebalancing means to rebalance said measuring circuit, mechanism for periodically recalibrating said measuring circuit comprising means for adjusting an electrical condition there-

of, a standard electrical unit, circuit controlling means for connecting said standard unit in said measuring circuit, the combination of a continuously rotating cam provided with a peripheral recess, a cam follower normally bearing upon the face of said cam and biased into said recess, means responsive to entry of said follower into said recess for actuating said circuit controlling means and for effecting an interconnection between said secondary movable member and said adjusting means, a second cam rotating continuously at a speed very much higher than said first mentioned cam, and a cam follower for said second cam acting conjointly with said first follower accurately to time the operation of said actuating means.

7. In a self-balancing measuring system including a measuring circuit, a galvanometer connected to measure the unbalance of said circuit, a driven shaft, mechanical relay apparatus, including a continuously rotating driving shaft, for periodically adjusting said driven shaft under control of said galvanometer, and means operated by said driven shaft to rebalance said measuring circuit, and mechanism operable by said relay apparatus for periodically recalibrating said measuring circuit including means for adjusting an electrical condition thereof, the combination of a rotatable cam, a double-worm gear reduction for driving said cam from said driving shaft, a cam follower, means controlled by said follower to effect an interconnection between said driven shaft and said adjusting means, a second cam driven by the intermediate worm wheel of said gear reduction, and a follower for said second cam acting conjointly with said first follower accurately to phase the operation of said interconnecting means with respect to the cycle of operation of said mechanical relay apparatus.

8. In a self-balancing measuring system including a measuring circuit, a primary member movable from a neutral position in accordance with variations in magnitude of a condition under measurement as determined by said measuring circuit, a secondary rotatable structure including means for rebalancing said circuit, and operating means controlled by said primary movable member for operating periodically said secondary structure to rebalance said measuring circuit, mechanism for periodically recalibrating said measuring circuit, circuit controlling means for completing connections for said recalibration of said measuring circuit, and a rotatable adjustable impedance interconnected with said measuring circuit, the combination of a support for said impedance pivoted about an axis parallel to said rotatable structure, and means operating intermittently to actuate said circuit controlling means and to move said support about its pivot to effect a driving engagement between said rotatable structure and said rotatable impedance.

9. In a self-balancing measuring system including a measuring circuit, a primary member movable from a neutral position in accordance with variations in magnitude of a condition under measurement as determined by said measuring circuit, including means for rebalancing said circuit, a secondary rotatable structure, means controlled by said primary movable member for periodically actuating said secondary structure to rebalance said measuring circuit, mechanism for periodically recalibrating said measuring circuit, circuit controlling means for completing recalibrating connections for said measuring cir-

cuit, a rotatable adjustable impedance interconnected with said measuring circuit, the combination of a support for said impedance pivoted about an axis parallel to said rotatable structure, and biased for movement about its pivotal axis to effect a driving engagement between said rotatable structure and said rotatable impedance, a continuously rotating cam, and means including a cam follower normally restraining said pivoted support from movement about its pivotal axis but intermittently releasing the same for recalibration of said measuring circuit.

10. In a self-balancing measuring system including a measuring circuit, a primary member movable from a neutral position in accordance with variations in magnitude of a condition under measurement as determined by said measuring circuit, a secondary movable member, circuit-rebalancing means operable thereby, operating means controlled by said primary movable member for periodically operating said secondary member to rebalance said measuring circuit, mechanism for periodically recalibrating said measuring circuit and including means for adjusting an electrical condition thereof, circuit controlling means for completing recalibration connections for said measuring circuit, the combination of a continuously rotating cam, a cam follower, means controlled by said follower to actuate said circuit controlling means, other means also controlled by said follower to effect an interconnection between said secondary movable member and said adjusting means, a second cam rotatable with said first cam but having an operating element retarded in phase with respect to that of said first-named cam, and a follower for said second cam controlling said interconnecting means conjointly with said first-named cam and follower.

11. In a self-balancing measuring system including a measuring circuit, a primary member movable from a neutral position in accordance with variations in magnitude of a condition under measurement as determined by said measuring circuit, a secondary movable structure including means for rebalancing said circuit, means controlled by said primary movable member for periodically operating said secondary structure to rebalance said measuring circuit, mechanism for periodically recalibrating said measuring circuit including means for adjusting an electrical condition thereof, circuit controlling means for completing recalibrating connections for said measuring circuit, the combination of a pivotally mounted member biased to move about its pivot and to actuate said circuit controlling means, an auxiliary pivotally mounted member biased to move about its pivot and to effect an interconnection between said secondary movable structure and said adjusting means but normally restrained by said first-named pivotally mounted member, a continuously rotating cam, means including a cam follower therefor normally restraining said first-named pivotally mounted member from motion about its pivot and timing its operation, a second cam rotating with said first-named cam but having an operating element retarded in phase with respect thereto, and a follower for said second cam normally restraining said auxiliary pivotally mounted member from motion about its pivot and timing its operation with respect to that of said first-named pivotally mounted member.

12. A multiple-point measuring apparatus comprising a rotatable structure provided with a

plurality of spaced peripheral marking elements, a pivotal support for said rotatable structure, means for carrying a record chart, means supporting said structure and its support for displacement across said chart, actuating mechanism effective upon each operation thereof to oscillate said support to bring said structure into registration with said record chart and including a ratchet and pawl mechanism operable currently with oscillation of said structure into and out of registration with said chart for rotating said structure through an angle equal to the angular spacing of said marking elements, a continuously rotating shaft, a cam operated by said shaft, and a cam follower therefor periodically operating said actuating mechanism.

13. A multiple-point measuring apparatus comprising a rotatable structure provided with a plurality of spaced peripheral marking elements, a pivotal support for said rotatable structure, a shaft connected to rotate said structure and along which said support is slideable, means for carrying a record chart, an oscillatable member having a sliding engagement with said support, actuating mechanism including a crank secured to said oscillatable member to bring said rotatable structure into registration with said record chart and a ratchet and pawl mechanism respectively secured to and supported by said shaft to rotate said structure step-by-step, a continuously rotating shaft, a cam operated by said continuously rotating shaft, and a cam follower therefor connected to operate said actuating mechanism.

14. In a multiple-point measuring apparatus comprising a rotatable structure provided with a plurality of spaced peripheral marking elements, a shaft connected to rotate said structure, a carriage slideable along said shaft, means for carrying a record chart, the combination of a support for said rotatable structure pivotally supported from said carriage, an oscillatable shaft having a longitudinal slot, said carriage having an element engaging said oscillating shaft to prevent rotation of said carriage and said support having an element engaging said slot, actuating mechanism including a crank arm secured to said oscillatable shaft to effect registration between said chart and said structure and a ratchet and pawl mechanism connected to said first-named shaft to effect step-by-step rotation thereof, a continuously rotating shaft and means operated by said continuously rotating shaft for periodically operating said actuating mechanism.

15. In a multiple-point measuring apparatus comprising a rotatable structure provided with a plurality of spaced peripheral marking elements, means for carrying a record chart, means for moving said structure with respect to said chart, the combination of an actuating mechanism effective upon each operation thereof to bring said rotatable structure into registration with said record chart and to rotate said structure through an angle equal to the angular spacing of said marking elements, said mechanism including a pivoted lever biased to an operating position, a continuously rotating cam disc having a peripheral recess, a cam follower normally bearing upon the face of said disc and restraining said lever and releasing the same upon registration with said recess, and an auxiliary cam for disengaging said follower from said recess.

16. In a mechanical relay operated multiple-point measuring apparatus comprising a rotatable structure provided with a plurality of spaced peripheral marking elements, means for carrying

a record chart, means for moving said structure with respect to said chart, the combination of an actuating mechanism effective upon each operation thereof to bring said rotatable structure into registration with said record chart and to rotate said structure through an angle equal to the angular spacing of said marking elements, said mechanism including a pivoted lever biased to an operating position, a continuously rotating cam, a cam follower therefor periodically operating said actuating mechanism, a second cam rotating continuously at a speed very much higher than said first-named cam, and a cam follower for said second cam acting conjointly with said first follower accurately to time the operation of 15 said actuating mechanism.

17. In a mechanical relay operated multiple-point self-balancing measuring system, including a continuously rotating driving shaft, a rotatable structure provided with a plurality of spaced peripheral marking elements, means for carrying a record chart, and means operated by said driven shaft to move said structure with respect to said chart, the combination of an actuating mechanism effective upon each operation thereof to bring said rotatable structure into registration with said record chart and to rotate said structure through an angle equal to the angular spacing of said marking elements, a rotatable cam operated by said driving shaft but 30 at a reduced speed, a cam follower therefor controlling the operation of said actuating mechanism, a second cam operated by said driving shaft at a speed of a higher order of magnitude than said first cam, and a follower for said second cam acting conjointly with said first follower accurately to phase the operation of said actuating mechanism with respect to the cycle of operation of the mechanical relay.

18. In a mechanical relay operated multiple-point self-balancing measuring system, including a continuously rotating driving shaft, a rotatable structure provided with a plurality of spaced peripheral marking elements, means for carrying a record chart, means for displacing said structure across the chart, the combination of an actuating mechanism effective upon each operation thereof to bring said rotatable structure into registration with said record chart and to rotate said structure through an angle equal to the angular spacing of said marking elements, a rotatable cam, a worm and worm wheel for driving said cam from said driving shaft, a cam follower therefor controlling the operation of said actuating mechanism, a second cam secured to and rotatable with said driving shaft, and a cam follower for said second cam acting conjointly with said first follower accurately to phase the operation of said actuating mechanism with respect to the cycle of operation of the mechanical relay.

19. In a multiple-point recorder having a rotatable structure provided with a plurality of peripherally spaced marking elements, the combination of a shaft, a carriage slidably supported on said shaft, a frame pivotally mounted from said carriage and having provisions for rotatably supporting said structure, a driving gear rotatable with said shaft and slideable with said carriage a cooperating driven gear journaled in said frame and meshing with said driving gear substantially at the pivotal axis of said frame for rotating said structure, an elongated member disposed parallel to said shaft, said frame having at least one extension cooperating with said member to predetermine the position of said frame.

means for moving said member and by said at least one extension to rotate therewith said frame from said predetermined position, and ratchet means supported by said shaft and operable only upon return movement of said frame to said predetermined position for rotating said shaft an amount sufficient to drive said structure an amount equal to the angular displacement between said marking elements.

20. In a multiple-point recorder having a chart-support, a carriage, means mounting said carriage for transverse movement across the chart, a frame pivotally mounted from said carriage, a print wheel journaled in said frame with its axis of rotation normal to the chart, said print wheel having a plurality of angularly disposed marking elements disposed on a beveled face thereof, and means for actuating said frame to move a selected one of said elements into and out of printing engagement with the chart.

21. In a multiple-point recorder having a chart-roll disposed adjacent the front thereof, a carriage, means mounting said carriage for transverse movement across the chart, a frame pivotally mounted from said carriage, a print wheel journaled in said frame with its axis of rotation normal to the chart and normal to the pivotal axis of said frame, and means cooperating with said frame for normally retaining said print wheel in a non-printing position, for bodily moving said print wheel downwardly therefrom to a position substantially below the top of and in front of said roll to print on the chart a record, and for returning said wheel to said non-printing position to render immediately visible on said chart said printed record.

22. In a multiple-point recorder having a multiple point recording element assembly comprising a rotatable structure provided with a plurality of spaced peripheral marking elements, the combination of a carriage, a support for said structure pivotally mounted from said carriage, a driving gear journaled in fixed position with respect to said carriage, and a driven gear journaled in said support for rotating said structure and meshing with said driving gear substantially at the pivotal axis of said support.

23. In a multiple-point recorder including a rotatable structure provided with a plurality of spaced peripheral marking elements, the combination of a carriage, a support for said structure pivotally mounted from said carriage, an inking device supported from said carriage for cooperation with said rotatable structure, and means for moving said support about its pivot to effect a registration of one of said marking elements with a record chart and to effect engagement and disengagement of one of said elements with said inking device.

24. In a multiple-point recorder including a recording element assembly comprising a rotatable print wheel provided with a plurality of spaced peripheral marking elements, the combination of a carriage, a support for said print wheel pivotally mounted from said carriage, a rotatable structure provided with a plurality of inking pads similar in number and spacing to said marking elements, said structure being pivotally supported from said carriage in cooperative relation with said marking elements, means for pivotally moving said support to effect engagement and disengagement of said inking pads and marking elements and to effect registration of the latter with a record chart, and means for rotat-

ing said print wheel and said structure in synchronism.

25. In an instrument having a member movable in accordance with unbalance of a balanceable network, the combination of a calibrating impedance for said network, an arm supporting said impedance for movement into and out of driving engagement with said member, an actuating arm normally biasing said supporting arm to a position to retain said impedance out of engagement with said member, a calibrating switch for said network operatively associated with said arm, a control member biased towards said actuating arm with sufficient force to operate said switch, and releasable means for retaining said control member in a position ineffective to cause said operation of said switch.

26. In an instrument having a member movable in accordance with unbalance of a balanceable network, the combination of a three-part calibrating device, one part comprising a pivoted switch-actuating arm, a second part comprising a pivoted support for an impedance device, and the third part comprising a control arm pivoted about the same axis as said first part for moving said first part, a spring interconnecting said first and second parts, a second spring biasing said first part into engagement with said second part, and a third spring for moving against the bias of said first and second springs said first and third parts into switch operating positions, and means for successively releasing and thereafter moving out of said switch operating position said third part.

27. In an instrument having a member movable in accordance with unbalance of a balanceable network, the combination of an adjustable impedance, an arm supporting said impedance for movement into and out of driving engagement with said member, a switch for completing a circuit including said impedance, an actuating arm for said switch normally engaging said supporting arm to retain it in a position with said impedance out of said engagement with said member, a control member biased toward said actuating arm with sufficient force to operate said switch, releasable means for retaining said control member in a position ineffective to cause operation of said switch actuating arm, said control member upon release thereof operating said actuating arm to actuate said switch, and means for retaining said supporting arm in a position with its said impedance out of said driving engagement for a time interval after operation of said switch by said actuating arm.

28. In an instrument having a member movable in accordance with unbalance of a balanceable network, the combination of an adjustable impedance, an arm supporting said impedance for movement into and out of driving engagement with said member, a switch for completing a circuit including said impedance, an actuating arm for said switch biased to a first switch-operating position and normally engaging said supporting arm to retain said impedance out of said driving engagement, a control member biased for movement into engagement with said actuating arm with sufficient force to move said arm against its bias to a second switch-operating position, a first cam releasably retaining said control member in a position to prevent operation of said switch to its second position, a second cam releasably retaining said supporting arm and its impedance out of said driving engagement, means for driving said cams with said second

cam retarded in phase with respect to said first cam to release said supporting arm an interval after operation of said switch, and means operable when said actuating arm occupies said second position for biasing said supporting arm and its impedance into said driving engagement with said first-named member.

29. In a self-balancing measuring system including a measuring circuit, a pointer movable in response to unbalance of said circuit, a driven member, and mechanical relay apparatus, including means for periodically clamping said pointer in fixed position, and for periodically adjusting said driven shaft under the control of said pointer, the combination of a calibrating impedance for said network, an arm supporting said impedance for movement into and out of driving engagement with said driven member, means including an actuating arm normally biasing said supporting arm to a position to retain said impedance out of said driving engagement, a calibrating switch for said network operatively associated with said arm, a control member biased towards said actuating arm with sufficient force to produce operation of said switch by said arm, releasable means for retaining said control member in a position ineffective to cause operation of said switch and for releasing said control member at a time when said pointer is clamped in its fixed position, and means operable as said switch is operated for retaining said supporting arm and its impedance out of said driving engagement until after completion of the adjustment of said driven shaft initiated by the last-preceding operation of said clamping means.

30. In a multiple-point recorder having a rotatable structure provided with a plurality of peripherally spaced marking elements, the combination of a shaft, a carriage slidably supported on said shaft, a frame pivotally mounted from said carriage and having provisions for rotatably supporting said structure, driving means interconnecting said shaft and said structure, an elongated member disposed parallel to said shaft, said frame having at least one extension forming a driving connection between said frame and said member which is maintained during sliding movement therebetween, means for moving said member to rotate said frame and said rotatable structure into and out of a marking position, and guiding means cooperatively associated with said elongated member to retain said carriage in a predetermined position during rotation of said frame.

31. In a multiple-point recorder having a rotatable structure provided with a plurality of peripherally spaced marking elements, the combination of a shaft, a carriage slidably supported on said shaft, a frame pivotally mounted from said carriage and having provisions for rotatably supporting said structure, driving means interconnecting said shaft and said structure, an elongated member disposed parallel to said shaft, said frame having at least one extension forming a driving connection with said shaft which is maintained during sliding movement of said frame with respect to said member, means for moving said member to rotate said frame and said rotatable structure into and out of a marking position, guiding means cooperatively associated with said member to retain said carriage in a predetermined position irrespective of relative rotation between it and said pivoted frame, and driving means operable in succession to rotate said shaft a predetermined amount and to actuate said

member-moving means for movement of said frame and said rotatable structure into and out of said marking position.

32. In a multiple-point recorder having a rotatable structure provided with a plurality of peripherally spaced marking elements, the combination of a shaft, a carriage slidably supported on said shaft, a frame pivotally mounted from said carriage and having provisions for rotatably supporting said structure, driving means interconnecting said shaft and said structure, an elongated member disposed parallel to said shaft, said frame having at least one extension forming a driving connection with said member which is maintained during sliding movement of said frame with respect to said member, means for moving said member to rotate said frame and said rotatable structure into and out of a marking position, guiding means cooperatively associated with said member to retain said carriage in a predetermined position during relative rotation between it and said pivoted frame, driving means operable periodically to rotate said shaft in one direction by predetermined amounts and between each successive rotation thereof to actuate said member-moving means for movement of said frame and of said rotatable structure into and out of said marking position, a selector switch operable through a plurality of positions, means operable in response to each movement of said shaft for operating said selector switch from one to another of its positions, and releasable means operable periodically to prevent operation of said shaft and said member moving means by said second-named driving means to retain for a predetermined time interval said rotatable structure, said selector switch, and said member in fixed positions, and effective upon release thereof to re-establish operation under the control of said second-named driving means.

33. In a measuring apparatus having a mechanical relay, including balancing means, for periodically rebalancing a measuring circuit unbalanced by successive association therewith of elements respectively responsive to a plurality of conditions, a print wheel operable into and out of a printing position to produce a mark for each of said conditions, the combination of ratcheting means for advancing said print wheel after each of said printing operations, a control switch driven jointly with said print wheel for connecting in sequence each of said elements to said network, a cam, a cam-follower biased into engagement therewith, means actuated by said cam-follower for controlling said printing operations of said print wheel, means for calibrating said network including a calibrating switch and a calibrating impedance respectively operable into and out of calibrating positions, releasable means cooperating to retain said calibrating switch and said impedance out of said calibrating positions and including cam-operated means phased with respect to said first-named cam for releasing said releasable means first to operate said calibrating switch and thereafter to operate said impedance to said calibrating position, and means operable upon release of said releasable means for restraining operation of said ratcheting means and of said cam-follower during operation of said calibrating means.

34. In a self-balancing measuring system including a measuring circuit, a member deflecting in response to unbalance of said circuit, a driven member, and mechanical relay apparatus, including means for periodically clamping said

deflecting member in fixed position and for periodically adjusting said driven member under the control of said deflecting member, the combination of a plurality of condition-responsive elements, a selector switch for associating with said circuit in sequence each of said elements, a print wheel operable into and out of a printing position to produce a mark for each of said condition-responsive elements, ratcheting means for advancing said print wheel and said selector switch after each of said printing operations, means including a cam, and a cam-follower biased into engagement therewith and controlled thereby for operating said print wheel into and out of said printing position, means for calibrating said network including a calibrating switch and a calibrating impedance respectively operable into and out of calibrating positions, releasable means cooperating to retain said calibrating switch and said impedance out of said calibrating position and including cam-controlled means phased with respect to said clamping means and with respect to said first-named cam and said cam-follower for releasing, at a time when said deflecting member is clamped in a fixed position and at a concurrent time when said print wheel is out of said printing position, said releasable means first to operate said calibrating switch to said calibrating position and a time interval thereafter to operate said impedance to its calibrating position, means operable substantially concurrently with release of said releasable means for restraining operation of said cam-follower and of said ratcheting means during operation of said calibrating means, and means for moving said calibrating switch and impedance out of their calibrating positions and substantially concurrently to free said cam-follower and said ratcheting means from said restraining means.

35. In a multiple-point recorder including a rotatable drum for carrying a record chart, the combination of a multiple-point recording element assembly comprising a carriage movable longitudinally of said chart drum, a support pivotally mounted from said carriage, a print wheel journaled in said support and disposed to register with said chart upon pivotal movement of said support, said print wheel lying in a plane substantially parallel to the axis of said chart drum, and means for moving said support and print wheel into and out of printing position, movement of said print wheel away from said chart immediately exposing the printed record to view.

55 36. In a multiple-point recorder having a multiple-point recording element assembly comprising a rotatable structure provided with a plurality of spaced peripheral marking elements, the combination of a carriage adapted for transverse movement across a record chart, a support for said structure depending from and pivotally mounted on said carriage about an axis parallel to its direction of motion, a driving gear associated with said carriage and journaled about an axis parallel to the direction of motion of said carriage, and a driven gear for rotating said structure journaled in said support about an axis normal to said direction of motion and meshing with said driving gear substantially at the pivotal axis of said support.

70 37. In a multiple-point recorder having a multiple-point recording element assembly comprising a rotatable structure provided with a plurality of spaced peripheral marking elements, the combination of a carriage, a support for said

structure pivotally mounted from said carriage, a driving gear disposed within said carriage and connected to rotate said structure, and an index plate and pin, one supported from said carriage and the other from said rotatable structure and engaging upon relative pivotal movement therebetween accurately to predetermine and register the position of each of said elements of said rotatable structure. 5

38. In a multiple-point recorder having a multiple-point recording element assembly comprising a rotatable structure provided with a plurality of spaced peripheral marking elements, the combination of a slideable carriage, a support for said structure pivotally mounted from said carriage, a driving gear slideable with said carriage and connected to rotate said structure, an index plate secured to and rotatable with said structure, an arm extending from said carriage and carrying a pin adapted to register with said index plate upon relative pivotal movement between said support and said carriage accurately to predetermine and register the position of each of said elements of said rotatable structure. 10 15 20

39. In a multiple-point recorder having a multiple-point recording element assembly comprising a rotatable structure provided with a plurality of spaced peripheral marking elements, the combination of a carriage, a support for said structure pivotally mounted from said carriage, 25 means for effecting step-by-step rotation of said structure, and an index plate and pin, one supported from said carriage and the other from said rotatable structure and engaging upon relative pivotal movement therebetween accurately to 30 predetermine and register the position of each of said elements of said rotatable structure. 35

40. In a multiple-point recorder having an exhibiting element visible from the front of said recorder, the combination of a print wheel comprising a disc-like member provided with a plurality of spaced marking elements disposed on the rim of said member, a plurality of identifying indicia, individual to said elements, disposed on a face of said member, means mounting said member for displacement across said element with said face of said member visible from the front of said recorder, means for moving said member to bring one of its marking elements into marking relation with said element, and a mask for said face of said member exposing the indicium corresponding to the operative marking element. 40 45 50

- riage, a support for said structure pivotally mounted from said carriage, a driving gear slideable with said carriage, a driven gear journaled in said support for rotating said structure and meshing with said driving gear substantially at the pivotal axis of said support, said carriage having provisions for supporting an inking device in cooperative relation with said marking elements, and means for moving said support about its pivotal axis to effect engagement and disengagement of said inking device with one of said marking elements and to effect registration of one of said elements of said rotatable structure and said record chart.
- 15 43. In a multiple-point recorder having a multiple-point recording element assembly comprising a rotatable print wheel provided with a plurality of spaced peripheral marking elements, the combination of a slideable carriage, a support for said print wheel pivotally mounted from said carriage, a driven gear journaled in said support for rotating said print wheel, a rotatable structure provided with a plurality of inking pads for successive and individual registration 20 with said marking elements, a driven gear journaled in said carriage for rotating said structure, and a common driving gear for said driven gears journaled in a fixed position with respect to said carriage and meshing with said first- 25 named driven gear substantially at the pivotal axis of said support.
- 30 44. In a multiple-point exhibiting instrument having means including a selector switch operable through a plurality of positions for the meas-

urement of the magnitudes of a plurality of conditions, and a visible scale, the combination of 5 rotatable means provided with a plurality of identifying indicia for and individual to said switch-positions, said indicia being concurrently visible with said scale, means movable across said scale for supporting said rotatable means, means for operating said selector switch from one position to another and for simultaneously 10 rotating said rotatable means, and a mask for said indicia exposing to view only that indicium which corresponds with the position of said selector switch.

45. In a multiple-point exhibiting instrument having means including a selector switch operable through a plurality of positions for the measurement of the magnitudes of a plurality of 15 conditions, and a visible scale, the combination of rotatable means provided on one face with a plurality of indicia for and individual to said 20 switch positions, means movable across said scale for supporting said rotatable means, with its said face generally parallel to that of said scale and concurrently visible therewith, means for operating said selector switch from one position to 25 another and for simultaneously rotating said rotatable means, and a mask supported by said movable means and exposing to view only that indicium which corresponds with the position of 30 said selector switch.

RAYMOND W. ROSS.

SOPHIE SEBERHAGEN,

*Executrix of the Last Will and Testament of
Sigurd H. Seberhagen, Deceased.*

CERTIFICATE OF CORRECTION.

Patent No. 2,113,069.

April 5, 1938.

RAYMOND W. ROSS, ET AL.

It is hereby certified that error appears in the printed specification of the above numbered patent requiring correction as follows: Page 2, first column, line 65, for the word "each" read the; page 11, second column, line 45, claim 11, strike out the article "a"; page 12, first column, line 51, claim 14, after "shaft" insert a comma; and second column, line 69, claim 19, before "a" insert a comma; and that the said Letters Patent should be read with this correction therein that the same may conform to the record of the case in the Patent Office.

Signed and sealed this 2nd day of August, A. D. 1938.

(Seal)

Leslie Frazer,
Acting Commissioner of Patents.
